UNITED STATES PATENT OFFICE

SAMUEL J. ROSENTHAL, OF BROOKLYN, NEW YORK

TASSEL-MAKING ART

Application filed November 12, 1928. Serial No. 318,684.

The invention relates to the art of making tassels for terminating cord units, such as used for ornamental calendar cord hangers; fastener cords for pamphlets or booklets, as for example, souvenirs, programs, menus and dance orders; bath-robe belts; curtain tie-backs; tie-cord for packages and other like purposes.

Among the objects of the invention there is provided a novel method of applying tassels on a cord and an improved machine whereby said method may be easily carried out to form a new article of manufacture, said machine comprising few and simple parts which shall operate in proper sequence performing a continuous process whereby tassels are secured along a cord and which shall be efficient and practical to a high degree. The term "cord" as used herein is intended to include braid, ribbon and other like materials.

In producing tassels embodying the invention, the units of desired lengths are made in a continuous row on an elongated cord so that they may be readily handled for dyeing and as an article of manufacture for applying to other objects, or for other purposes before being severed and finished. Thus the improved process differs essentially from the well understood hand manipulation methods of forming tassel units in which separate cord units are severed prior to individually forming the knotted tassels on the ends thereof.

Other objects of this invention will in part be obvious and in part hereinafter pointed.

The invention accordingly consists in the features of construction, combinations of elements and arrangement of parts which will be exemplified in the construction hereinafter described and of which the scope of application will be indicated in the following claims.

In the accompanying drawing, in which is shown various possible illustrative embodiments of this invention:

Fig. 1 is a front elevational view of a machine embodying the invention for producing tassels along a cord.

Fig. 1^a is a diagrammatic view of an in-

stallation for simultaneously forming two knotted tassels on a cord embodying the invention.

Figs. 2 and 2^a are front elevational views of knot tying portion of the machine showing the cord looping and knot tightening steps of the improved method, respectively.

Fig. 3 is a fragmentary top plan view of tassel material feeding and severing portion of the improved machine.

Figs. 4 and 4^a are fragmentary perspective views showing in detail successive steps in the tassel knot tying operation.

Figs. 5 and 5^a are perspective views of one form of knotted tassel, Fig. 5 showing the knot in loosened condition.

Figs. 6 and 6^a are perspective views, corresponding to Figs. 5 and 5^a, respectively, of another form of knotted tassel.

Figs. 7 and 7^a are perspective views corresponding to Figs. 5 and 5^a, respectively, of still another form of knotted tassel.

Fig. 8 is a perspective view showing a double cord loop tasseled construction embodying the invention.

Fig. 9 is a diagrammatic view showing adjacent knotted tassels constructed to extend in relatively opposite directions for terminating the cord unit ends.

Referring in detail to the drawing, 10 denotes an improved machine embodying the invention and used in carrying out the novel method for making tassels T firmly knotted in a suitable manner, as at K¹ and K² along a cord C. The cord C may be of any well known strand construction, or may comprise a suitable braid or ribbon. As here shown the cord comprises tightly twisted strands, each covered with a cotton or natural or artificial silk layer of any desired color or colors. The tassels T may be formed of loose threads of mercerized cotton, natural or artificial silk or other fibrous material bunched or bundled together and fixedly attached at spaced distance along the cord C by the knots K¹ and K².

Said knots comprise any suitable type of tie fastening construction, as for example, as is hereinafter described and shown in the drawing. The knotted structure shown in Figs. 5 and 5^a is seen to be formed by folding

bunched tassel threads lengthwise thereof with a bight B engaging the cord C, the free end portions E of each tassel T being drawn through a closed or twisted loop L of the cord C and tightened to form the knot K.¹

The machine 10 may be constructed of any suitably designed parts cooperatively actuated to knot the tassel T in spaced relation on the cord C. As here shown the machine 10 is seen to comprise mechanism I for supplying a continuous strand S for the bunches of tassel threads, mechanism II for severing the strand S into uniform lengths and feeding same in proper sequence in the tassel tying operating, mechanism III for retaining a portion of the cord C and forming a loop L in said portion of the strand, mechanism IV for entwining the severed bunches of threads of the strand S with the loop L of the cord and 20 tightly tying same to form the knotted tassel T, and mechanism V for feeding the cord C through the machine in cooperative timed relations with the movements of the mechanisms I, II, III and IV.

25 In carrying out the improved process and providing the machine 10 embodying the invention it is contemplated through mechanism I to supply either spooled threads (not shown), in the well understood manner, to 30 form the continuous strand S of threads fed to the machine to form the tasseis T or to use threads just as they come commercially in hanks thus eliminating the spooling operation. In the latter case the hanks are each 35 cut through, separated into small bunches and fed into a strand spinning device D of any well understood construction, such for example, as used in cotton and woolen textile mills for spinning yarns.

40 The mechanisms II, III, IV and V are carried on a frame 11 and are actuated by a suitable power transmission P through a main drive shaft 12 journaled in aligned bearing blocks 13 which are supported in spaced relation 45 on the frame 11.

Mounted to turn with the shaft 12 are cams 14, 15, 16 and 17 of any suitable well understood construction. Said cams engage with ends 18^a, 19^a, 20^a and 21^a, respectively, of the rods, 18, 19, 20 and 21, respectively. The 50 other ends 18^b and 19^b, of the rods 18 and 19, respectively, are suitably pivoted to arms 22^a and 23^a, respectively, of bell cranks 22 and 23, respectively.

55 The mechanism II includes the bell crank 22 mounted for rocking movement on a bearing 26 carried by the frame and has an arm 22^b suitably connected, as at 27, with one end 28^a of a slide shaft 28 for reciprocating the latter through a sleeve bearing 29 supported by or integrally formed with the frame 11. The other end 28^b of the shaft 28 terminates in folder fingers 30 and carries a knife blade 31. The latter is secured to the shaft 28 by an adjustable mounting piece 32 and cooper-

ates with another knife blade 33 for severing a portion of the strand S of the bunched loose threads from which the tassels T are made. The fingers 30 serve to fold the severed portion of the strand S about the cord C in the knot tying operation as will herein-after be more fully described.

The severed strand feeding portion of mechanism II may comprise gripper members 34 which are reciprocatingly carried on a rod 35, the latter being pivotally connected, as at 36, to the swinging end 37^a of a lever 37. The lever 37 is pivotally anchored as at 38 on the frame 11 and connects with one end, 39^a of a slide rod 39. The other end 39^b of said rod engages with a cam 40 driven from the main shaft 12 for actuating the gripping member 34 through the rod 39, lever 37 and rod 35, as is clearly shown in Fig. 3.

The mechanism III includes the bell crank 23 mounted for rocking movement, as on bearing 44 supported by the frame 11. Said member 23 has an arm 23^b connected in any suitable manner, as shown at 45, with one end 46^a of a sliding shaft 46 which extends through a bearing 47 carried by the frame 11. The other shaft end 46^b terminates in a forked hook member 46^c, the latter being adapted to engage with the cord C to form the closed or twist loop L therein. In making the twist loop L for knotting the tassel T, the shaft 46 and hook member 46^c is not only reciprocated but must also be rotated substantially through three-quarters of a turn or more. To this end the shaft 46 may have a suitably 100 splined connection with a pinion 48 mounted to turn therewith. Said pinion 48 meshes with a gear sector 49 which is swingably connected with one end 20^b of the cam rod 20.

The mechanism IV includes the cam 17 which engages one cam rod end 21^a, the other end 21^b of the rod 21 is suitably connected, as at 50, for swinging a lever 51 about its end 51^a pivoted on the frame 11. The free end 51^b of said lever is suitably connected as at 52 with one end 53^a of a rod 53, the latter being mounted for reciprocating movement through a bearing 54 extending from the frame 11. The other end of the rod 53 terminates in a gripper member 55 having a head 55^a, a collar 55^b mounted to slide on the rod 53 and to cooperate with the head to form gripping jaws for drawing the strand end portions E through the twist loop L of the cord and tightening the knot K in the manner as will hereinafter appear.

The gripper member 55 also includes a coil spring 56, a crank lever 57 and a buffer stop 58. The spring 56 is carried on the rod 53 between the collar 55^b and the bearing 54 and is normally in compression for urging the collar jaw 55^b against the head jaw 55^a. The bell crank lever 57 may be pivoted to the frame 11 as at 57^a and has one arm terminated by a latch 57^b for engaging a flange 55^c 130

of the collar 55^b for releasing the gripping action of jaw member when the rod 53 is in the retracted position as shown in Fig. 1. The other arm 57^c is adapted to abut the rod end 53^a for releasing the jaw member from the action of the latch 57^b on the advance movement of the rod 53. A tension spring 59 has its ends anchored between the bell crank arm carrying the latch 57^b and the bearing 54 for holding the latch in effective position in the path of movement of the collar flange 55^c.

The buffer stop 58 is slidably supported in a frame bearing 60 and is resiliently mounted by means of a suitable compression spring 58^c which is carried on the stop spindle 58^a between the bearing 60 and a collar 62 secured in one end of the spindle. A stop head 58^b which projects from the other end of the spindle is adapted to engage the collar flange 55^c for opening the gripper member 55 when the rod 53 is fully advanced and said member 55 is in position to engage the strand end portions E as is clearly shown in Fig. 2.

The mechanism V includes a double gripper for retaining the portion cord C while knotting a tassel T between the intervals of intermittent feeding by a winding device 66.

Said double gripper is seen to comprise spaced fixed jaws 61^a between which the forked hook member 46 moves for engaging with the portions of the cord C extending over said jaws in the path of travel of said member. Each jaw 61^a has a cooperating movable jaw 61^b which clamps the cord C between them during the knot tying operation. The jaws 61^b are moved in and out of effective clamping positions through a suitable linkage such as rod 63, and a bell crank 64 interconnecting said rod with a link 65 engaging with the cam 17 for actuating said gripper jaws 61^b as is clear from Fig. 1.

The mechanism V comprises a winding device 66 which may be of any well understood construction for intermittently feeding the cord C through the machine 10, as for example, including a roller 67 driven by a suitable sector gear 68 and pinion 69 from the rod 21 through a clutch 70 and a pressure roller 71 coacting with the roller 67. The cord C gripped between the rollers 67 and 71 is fed with the rotation of the roller 67 through the intermittent reciprocation movement of the rod 21 of the mechanism IV. A rod 72 having an end 72^a adjustably secured to the sector gear 68 connects the rod end 21^b with the latter as is shown in Fig. 1.

The operation of the improved machine 10 in carrying out the novel knot tying process embodying the invention will now be clear.

The cord C is positioned in the machine 10 to extend through the gripper jaws 61^a and 61^b and is passed between the rollers 67 and 71 of the winding device 66. Starting with the mechanisms of the machine 10 in the relative positions shown in Fig. 1, the gripper

jaws 61^a and 61^b being closed sufficiently to permit slippage of the cord C therethrough, on rotating of the shaft 12, the cams 15 and 16 of the mechanism III cause the hook member 46^c to descend, engage the portion of the cord C between said jaws 61^a and 61^b and to rotate three-quarters of a turn to form a closed or twist loop L therein as shown in Figs. 2 and 4. The gripper jaws 61^a and 61^b are next actuated to stop any further slippage of the cord C therethrough. Meanwhile, the gripper member 55 due to the action of the cam 17 of the mechanism IV is advanced from its retracted position shown in Fig. 1 to project its head 55^a through the cord loop L as shown in Fig. 2. Here head 55^a engages with a severed portion of the bunch strand S which has been folded about the cord adjacent the loop L by the mechanism II. As the member 55 is again retracted it grips the ends of portion E of the severed strand as shown in Fig. 4 and on further retractive movement draws said end portions E through the loop L as seen in Fig. 4^a. The retractive movement of the gripper members 55 thereafter continues to tighten the knot K¹ as shown in Fig. 2^a, until the latch 57^a engages the collar flange 55^c, then on advanced movement of the member 55, the tassel T is released. Next the gripper jaws 61^b are raised to permit the cord C to be drawn a definite length through the machine by the winding device 66 of mechanism V which is made effective by the actuation of the roller 67 through the rod 70.

While the loop L is being formed, the mechanism II through cam 14 operates the knife blade 31 for shearing a portion of the strand held while the gripper member 34 holds the end of the strand S as seen from Fig. 3. The strand severing operation is followed by the folding of the severed strand portion about the cord C. This is accomplished by the fingers 30 which engage the end portion E of the severed strand and carry them down so as to be in position for engaging with the gripper member 55 in the manner explained above. The operations of the mechanisms are repeated and are timed in proper sequences to make the process a continuous one.

It should be noted that the operation of the machine 10 ties the knotted tassels T so that they extend in one general direction with respect to the cord C. When it is desired to form cord units of definite lengths with a tassel T terminating each end, any one of the following methods will accomplish this result. First, the cord C with the spaced tassels T formed as above described, may be fed through the machine 10 in such a manner that spaced tassels T are applied thereto by knots K². These tassels differ from tassels having knots K¹ in that they extend in relatively opposite directions. Fig. 9 shows the

formation of the tassels with knots K^1 and K^2 . Of course machine 10 may be readily designed to alternately form tassels with knots K^1 and K^2 , but preferably two machines 10 are operated in series as shown diagrammatically in Fig. 1^a, so that each machine makes one type of knotted tassel on the same cord, thus the production is speeded up and both types of tassels with knots K^1 and K^2 are simultaneously produced. After the tassels T have been firmly knotted to the cord C, the latter is cut at X and Y between the adjacent knots K^1 and K^2 thereby forming cord units having the tassels T extending outwardly from the ends thereof.

Figs. 6 and 6^a show another type of knotted tassel structure T² for tying the tassels to the cord. This differs from the knotted structure described above and shown in Figs. 5 and 5^a, in that the cut end X² of the cord C extends down into the loop L² instead of passing outwardly away from the loop L of the knots K^1 or K^2 of tassels T.

Still another type of knotted tassel structure T³ tied to the cord is shown in Figs. 7 and 7^a. Here no closed or twisted loop is formed but instead the cord C is simply folded with a bight, as at F, said fold engaging with the fold bight B of the severed bunch strand in the same manner as in forming an ordinary square knot. After such a knotted tassel T³ has been tightened the bights F and B of the folds firmly retain the tassel knotted structure against disengagement.

For some purposes it is desirable to provide tassel cord units with double loops as for example, as shown in Fig. 8. Here the cord C has loops D formed therein, each loop having a tassel T⁴ terminating the ends thereof. These tassels T⁴ may be tied in any suitable way as by means of a square knot. After the double loops D and tassels T⁴ are made on the cord C, the units are separated and completed by severing the cord at X³.

It will thus be seen that there is provided a method, a device for carrying out said method, and article of manufacture in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A machine for making knotted tassels comprising a feeding mechanism for advancing a cord through the machine a predeter-

mined distance, and means for tying bunches of threads with the cord to form tassels spaced along the cord corresponding to said predetermined distance.

2. In an apparatus of the character described, knotting means for tying bunches of threads to a cord to form spaced tassels thereon, said means having co-operating parts for tying adjacent tassels to extend in relatively opposite directions.

3. In a knotting machine of the character described, for tying spaced tassels on a cord, means for forming a loop in the cord, and means for engaging a bunch of threads about the cord and through the loop to form a knotted tassel with said threads.

4. In a knotting machine of the character described, for tying spaced tassels on a cord, means for twisting spaced loops in the cord, and means for engaging a bunch of threads about the cord and through each of the loops to form knotted tassels, said engaging means forming the adjacent tassels to extend in relatively opposite directions.

5. A machine for making knotted tassels comprising in combination, means for releasably holding a length of cord, a rotary reciprocating means for engaging and twisting a loop in said cord length, means for feeding a bunch of threads adjacent the formed cord loop, means for folding the threads about the cord with the end portions of the threads in register with the opening of the cord loop, and means for drawing the thread ends through the loop for knotting the threads therewith to form a tassel.

6. A machine of the character described, in combination means for feeding bunches of threads, means for knotting each bunch fed on a cord to form a tassel at spaced distances apart, and means for feeding the cord and tassels through the machine.

7. A machine of the character described, in combination spinning means for forming a strand of threads, means for severing the strand in uniform lengths, means for intermittently feeding the severed lengths, means for knotting each strand length fed on a cord to form a tassel at spaced distances apart, and means for feeding the cord and tassels through the machine in timed relation to the operations of the spinning, severing, strand length feeding and knotting means.

8. In an apparatus of the character described, knotting means for tying a bunch of threads to a cord to form a tassel, other knotting means for simultaneously tying another bunch of threads to form a second tassel on the cord a spaced distance from the first tassel with the adjacent tassels extending in relatively opposite directions.

9. A tassel machine comprising in combination, means for holding a length of cord, means for engaging and looping a portion of said cord length retained by said holding

70

means, means for folding a bunch of thread about the cord adjacent the loop, means for drawing the end portions of the threads through the loop and for tightening the engagement of the folded threads with the looped cord to form a knotted tassel.

10. A machine for making knotted tassels comprising in combination means for releasably holding a length of cord, a rotary reciprocating means for engaging and twisting a loop in said cord length, means for folding a bunch of threads on the cord adjacent one end of the cord loop, reciprocating means in and out through the loop for engaging and drawing the end portions of the threads through the loop for knotting the thread therewith to form a tassel, and means for feeding the cord and tassel thereon through the machine.

11. The art of making tassels for terminating cords, consisting in tying bunches of threads in spaced relation along a cord to form tassels, and severing the cord at each tassel to form units having each end thereof terminated by a tassel.

12. In the art of the character described, the step of tying bunches of threads in spaced relation along a cord to form tassels prior to severing the cord into predetermined unit lengths for terminating each end of the latter with a tassel.

13. In the art of making tassels for terminating cords, the step of tying bunches of threads in spaced relation along a cord with the adjacent thread bunches extending in relatively opposite directions prior to serving the cord into unit lengths.

14. The art of making tassels for terminating cords, consisting in tying bunches of threads in spaced relation along a cord with the adjacent thread bunches extending in relatively opposite directions, and severing the cord between said adjacent bunches to form units having an end thereof terminated by a tassel.

15. In the art of making tassels for terminating the cords, the step of looping a mid-section of a cord and engaging a bunch of threads about the cord and extending same through said loop to form a knotted tassel.

16. In the art of making tassels for terminating cords, the step of simultaneously knotting a plurality of bunches of threads on spaced portions of a cord to form tassels with the adjacent tassels extending in relatively opposite directions.

17. In the art of making tassels for terminating cords, the step of simultaneously knotting a plurality of spaced tassels on a cord with the adjacent tassels extending in relatively opposite directions, and severing the cord between said adjacent tassels for terminating the cut ends of the cord with a tassel.

18. As an article of manufacture, an elongated cord, and pairs of tassels secured in spaced relation on said cord, one tassel of

each pair being fastened to the cord to extend in a relatively opposite direction with respect to the other tassel.

19. In the art of tassel making, the step of simultaneously looping spaced portions of a cord and engaging separate bunches of threads with said cord loops to form knotted tassels.

In testimony whereof I affix my signature.

SAMUEL J. ROSENTHAL.
